DEFROSTER FOR REFRIGERATORS

R. Stuart Davis, Jr., 32021 Weston Drive,
Birmingham, Mich.

Filed Oct. 17, 1962, Ser. No. 72,162

Term of patent 14 years

(Cl. D67—2)

Fig. 1

Fig. 2

The other end view is substantially similar to the one shown.

I claim:

The ornamental design for a defroster for refrigerators, as shown and described.
